UNITED STATES PATENT OFFICE.

GUSTAVE E. ANDERSON, OF PHILADELPHIA, PENNSYLVANIA, ASSIGNOR
TO FAIRMOUNT MACHINE COMPANY, OF PHILADELPHIA, PENNSYLVANIA, A CORPORATION OF PENNSYLVANIA.

TAKE-UP MECHANISM FOR LOOMS.

SPECIFICATION forming part of Letters Patent No. 769,580, dated September 6, 1904.

Application filed December 7, 1903. Serial No. 184,181. (No model.)

To all whom it may concern:

Be it known that I, GUSTAVE E. ANDERSON, a citizen of the United States, residing in Philadelphia, Pennsylvania, have invented certain 5 Improvements in Take-Up Mechanism for Looms, of which the following is a specification.

The object of my invention is to so construct take-up mechanism for looms that any desired 10 change in the speed of take-up, and consequently any desired change in the number of picks of weft-thread in an inch of woven fabric, can be effected by change of one of the spur-wheels in the train of gears whereby 15 movement is transmitted from the ratchet-wheel forming the primary member of said train to the wheel on the shaft of the take-up roll, the wheels of the train being such that the number of teeth in the change gear-wheel 20 will represent the desired number of picks to the inch.

In the accompanying drawings, Figure 1 is a side view of sufficient of a loom to illustrate my invention; and Fig. 2 is a view of the same, 25 partly in end elevation and partly in section.

1 represents part of one of the side frames of the loom, and 2 part of the swinging lay, which carries a pin 3, engaging with a slotted lever 4, the latter being hung to a pin 5, which 30 is adjustable longitudinally in a slotted lug 6 on one of the bars of the frame 1. In addition to the slot 7, which engages the pin 3, the lever 4 has a slot 8 for the reception of a pin 9, which is adjustable in said slot 8 from and 35 toward the fulcrum-pin 5 of the lever, and said pin 9 carries a pawl 10, which engages with the teeth of a ratchet-wheel 11, the latter being mounted so as to be free to turn upon a stud 12, which is secured to and projects 40 from a slide 13 on the side frame 1 of the loom. Vertical adjustment of this slide 13 on the loom-frame is in the present instance effected by providing said frame with a vertical slot 14 for the reception of the bolt 15, whereby the 45 slide is secured to the frame, a lug 16 on the slide also entering said slot, as shown in Fig. 2, so as to insure the proper guidance of the slide in its vertical movement.

Hung to the fulcrum-pin 5 of the lever 4 is a detent 17, which engages with the teeth of 50 the ratchet-wheel 11 and prevents back movement of the same. Secured to the hub of the ratchet-wheel 11 is a pinion 18, and meshing with the latter is another pinion, 19, which is free to turn upon a stud 20, secured to and 55 projecting from the slide 13, said pinion 19 meshing with a spur-wheel 21, which is secured to a shaft 22 free to turn in a hanger 23, secured to the frame 1, as shown in Fig. 2, said shaft 22 also having a spur-pinion 24, 60 which meshes with a spur-wheel 25 on the shaft of the take-up roll 26.

The spur-wheel 21 constitutes the change-wheel of the gearing and has as many teeth as the desired number of picks per inch in the 65 fabric to be woven. The ratio of the spur-wheel 25 and pinion 24 being fixed and the number of teeth in the ratchet-wheel being also known, all that remains to be determined in order to permit of the use of a change- 70 wheel of the character described is the relation of the circumference of the take-up roll 26 to the number of teeth in the pinion 18, the pinion 19 being a negligible quantity, since it is employed simply for causing the 75 proper direction of rotation of the take-up roll and has no effect upon the speed of movement of the same. Assuming that C represents the circumference of the take-up roll, P the number of teeth in the pinion 18, R W 80 the number of teeth in the ratchet-wheel, and R the ratio between the wheels 24 and 25, the equation is as follows:
$$\frac{C \cdot P}{R \cdot W} = R.$$

Having thus described my invention, I claim 85 and desire to secure by Letters Patent—

1. Take-up mechanism for looms having as an element a change gear-wheel with the same number of teeth as the number of picks per inch in the fabric which is being woven, substantially as specified.

2. Take-up mechanism for looms comprising a ratchet-wheel constituting the primary element of the operating-gearing, a gear-wheel on the take-up-roll shaft, and intermediate gearing having a change-wheel with the

same number of teeth as the number of picks per inch in the fabric which is being woven, substantially as specified.

3. The combination in take-up mechanism for looms, of the take-up roll and the gear-wheel thereon, a ratchet-wheel constituting the primary member of the gearing, a pinion secured to said ratchet-wheel, gearing for transmitting motion from said pinion to the take-up roll, one of the members of said gearing being a change-wheel, a slide carrying the ratchet-wheel and its pinion and means for adjusting said slide from and toward the axis of said change-wheel, substantially as specified.

15 4. The combination in take-up mechanism for looms, of the take-up roll and the gear-wheel thereon, a ratchet-wheel constituting

the primary member of the gearing, a pinion secured to said ratchet-wheel, gearing for transmitting motion from said pinion to the take-up roll, one of the members of said gearing being a change-wheel, a slide carrying the ratchet-wheel and its pinion and adjustable from and toward the axis of said change-wheel, and a pinion also carried by the slide and interposed between the change-wheel and the pinion of the ratchet-wheel, substantially as specified.

In testimony whereof I have signed my name to this specification in the presence of two subscribing witnesses.

GUSTAVE E. ANDERSON.
